DIRECTIONAL SIGNAL FOR MOTOR VEHICLES

Original Filed Sept. 27, 1932

FIG. 1

FIG. 2

UNITED STATES PATENT OFFICE

2,190,862

DIRECTIONAL SIGNAL FOR MOTOR VEHICLES

Edward T. Condon, New York, N. Y.

Original application September 27, 1932, Serial No. 635,006. Divided and this application April 16, 1937, Serial No. 137,176

1 Claim. (Cl. 177—329)

The invention relates to directional signal devices for motor vehicles, more particularly to electrically operated devices whereby, for example, a right- or left-hand turn may be indicated at will to a succeeding or approaching vehicle as by operation of a suitable switch located conveniently to the operator of the vehicle.

The invention has for an object a simple and conveniently assembled structure embodying a design element illuminated when a signal is to be given.

A further object of the invention resides in the provision of a lens or design unit wherein and whereby the design element is so positioned as to be within a shadow area afforded by the positioning member for the lens element, which element is screened also thereby against light from associated signal lamps, if any.

Another object of the invention is to afford a rugged construction securing the shadow area without the usual projecting visor, and whereby the device is effective when mounted on a vehicle in any angular position with reference to the optical axis of the lens element by correspondingly rotating said lens element about said axis to locate the design element depicted thereon with reference to the housing.

Still another object of the invention resides in the construction of a design element retaining member which is suitably reinforced to stiffen the same, said construction affording at the same time a means for positioning the element to secure the shadow area and the screening effect aforesaid.

An object of the invention, also, is to afford a lamp retaining element adequately protecting the lamp and providing for its ready removal therewith to allow access to the lamp, there being afforded, also, ample space for the electrical conductors to said lamp.

In carrying out the invention, the signal device is constructed of two separable units constituting a lamp housing and the one affording a support for the other. This supported unit is in the nature of an open-ended cylinder having its edge turned over and inwardly directed a substantial distance toward the supporting unit to afford an abutment and a shadow area within the cylinder for the design element which is positioned therein against said abutment. The said open-ended cylinder carries also a lamp and a reflector behind the design element to illuminate the design thereon; and provision is made to removably hold the two units together.

The nature of the invention, however, will best

be understood when described in connection with the accompanying drawing, in which:

Fig. 1 is a front elevation showing the novel directional signal device.

Fig. 2 is a horizontal section thereof.

Fig. 3 is an exploded view of the lamp housing assembly.

Fig. 4 is a vertical section of the signal device.

Referring to the drawing, the novel signal device comprises a housing 10, for example, of the acorn type and having an inner portion 11 in the nature of a bowl, while the outer portion 12 is separable and in the nature of a barrel or open cylinder, for example, with its outer portion turned inwardly and backwardly upon itself as 13 at 13 to afford a shoulder for a lens 14. The turned-back portion 13, moreover, sets this lens back an appreciable distance and affords a shadow box for the design so that undesired illumination of the same from an external source will be materially reduced and no confusion as to signals results.

This lens may be of the vertically fluted type adapted to spread light rays more or less longitudinally of the support for the purpose herein-after set forth, and the fluted portion is provided only on the rear or inner surface, as shown.

The particular design of the signal to be displayed through the lens may be afforded by means of a stencil plate 15 located immediately behind the lens 14 which is preferably sandblasted over its inner face, and the surface of the stencil plate adjacent the lens being preferably blackened while its opposite surface which faces the inner portion of the bowl 11 is preferably polished to reflect back any light into the interior. In the provision of a sand-blasted or etched rear surface of the design, any external illumination will be prevented from passing through with any degree of intensity.

The desired color in which the signal is to be displayed may conveniently be obtained from a transparent or translucent colored disk 20 located behind the lens, said disk being preferably of so-called stipple glass with the stippled surface facing inwardly toward the interior of the housing. This disk, furthermore, is preferably displaced an appreciable distance from the lens by a gasket 21 or the like to afford an intermediate air chamber whereby there is prevented appreciable illumination of the interior colored lens by any external light which might enter through the design.

The desired illumination for a signal is obtained from electric light 22 carried by a par-

abolic reflector 23 and mounted with its filament substantially in the focus of the reflector, the light and reflector being positioned behind the colored disk 20. Reflector 23 is provided with a flange 24 bearing upon the disk 20 at its circumference; and all of the members are retained in position by means of this flange through the action of a resilient strap member 25 which is adapted to fit over the bottom of the reflector and is removably secured at its opposite ends beneath the inturned inner edge 26 of member 12, the reflector sliding slightly when pressure is exerted upon the spring strap allowing its tongue to be inserted or withdrawn. A suitable longitudinal key 27 in the inner wall of the housing member 12 serves to properly locate the various elements of this assembly which may be slotted to fit the said key.

The hereinbefore-described assembly, moreover, makes for a compact unit which is readily joined to the bowl portion 11 of the housing, for example, by means of a screw 30 adapted to pass through an opening 31 in the wall of the bowl

and threaded into the strap 25 holding the unit together. Furthermore, in uniting the two housing portions, a prong 32 at the end of the strap opposite the screw-receiving end, and projecting radially over the adjacent edge of the housing portion 12, is adapted to enter a slot 33 in the wall of the bowl portion 11 of the housing and thus further insure the union of the two members.

The present application is a division of my copending application Serial #635,006, filed September 27, 1932 and issued April 20, 1937 as Patent No. 2,077,461.

I claim:

A signal lamp for motor vehicles including a cylinder having one end portion turned over and inwardly directed a substantial distance toward the other end, signal indicia means supported at the termination of the inwardly directed portion, the latter adapted to form a shadow area to reduce undesired illumination of the signal indicia from external sources.

EDWARD T. CONDON.
